UNITED STATES PATENT OFFICE.

JOSEPH THOMAS, OF NEW YORK, N. Y., ASSIGNOR TO THE THOMAS MACHINE CUTTING COMPANY.

CLOTH-CUTTING MACHINE.

SPECIFICATION forming part of Letters Patent No. 340,964, dated April 27, 1886.

Application filed February 8, 1886. Serial No. 191,187. (No model.)

To all whom it may concern:

Be it known that I, JOSEPH THOMAS, a citizen of the United States, and a resident of New York, in the county of New York and State of New York, have invented certain new and useful Improvements in Cloth-Cutting Machines; and I do hereby declare that the following is a full, clear, and exact description of the invention, which will enable others skilled in the art to which it appertains to make and use the same, reference being had to the accompanying drawings, which form a part of this specification.

My invention relates to that class of machines for cutting cloth or other materials in which an endless cutting-blade is employed, traveling around a series of rollers journaled on an approximately-circular supporting-frame; and it consists, first, in a machine of this class comprising a circular frame having an opening in one of its sides, an endless belt passing around a series of rollers journaled upon one side of the said frame, in through the opening in the frame, and over a roller journaled therein opposite the said opening, and an endless cutting-blade fitting tightly around the outside of and traveling with the said endless belt, (which is formed of leather or other suitable material to adapt it to form a cushion of sufficient yielding qualities,) except at the point where the cutting-blade spans the opening in the circular frame.

My invention further consists in means for adjusting the tension of the cutting-blade and endless belt, and in certain other improvements, which will all be hereinafter fully described, and pointed out in the claims.

Referring to the accompanying drawings, Figure 1 is a side view of my improved machine for cutting cloth. Fig. 2 is a top view of the same, and Fig. 3 is a perspective view of the forward portion of the machine.

The same letters of reference indicate corresponding parts in all the figures.

Referring to the several parts by letter, A represents the base of the machine, upon which is secured in a vertical position the circular frame B, having the opening B' in one of its sides, through which the table C, on which the material to be cut is supported, extends.

To one side of the lower half of the frame

B are journaled, on short stub-axles D', the rollers D, the said rollers being arranged in a semicircular form and having their outer ends formed with flanges D², which serve to prevent the endless belt from slipping or working off of the said rollers, as will be hereinafter described. Upon the same side of the upper half of the frame B is secured at one of its ends, by means of the pivot-bolt E, the two 55 semicircular frame pieces F, which form the upper roller-frame, and between which are journaled, on short stub-axles G, the upper series of rollers, H, which are arranged in a semicircular form, as shown, and which are 60 here shown as without flanges, as the outer frame-piece F prevents the endless belt from working off of the said rollers. It is obvious, however, that the outer frame-piece F might be dispensed with, and the outer ends of the 65 rollers H formed with flanges, like the lower series of rollers. The opposite end of the inner frame-piece F to that which is supported by the pivot-bolt E rests upon and is supported by a block, I, secured to the side of the 70 frame B, and a slotted plate, J, is secured by a pivot-bolt passing through its upper end to the said end of the roll-frame piece F, and extends down over the block I, a set-screw, K, passing through the slot of the said plate into 75 the said block, by which arrangement the outer end of the upper roller-frame may be raised or lowered, to adjust the tension of the cutting-blade and endless belt, and secured in its adjusted position.

Diametrically opposite to the opening in the frame B is journaled, against the side of the said frame, a disk, M, (the frame B being formed at that point with a collar or projecting portion, which brings the disk M out in the same 80 plane as the circular series of rollers which carry the endless belt and cutting-blade,) and a smaller disk, N, is secured upon the outer face of the disk M, concentric with it, and an outwardly-projecting bracket, O, projects from 85 the outer side of the frame B, opposite to the said disks, and has a pulley, P, journaled upon its side, which pulley receives its motion from the driving-power, and has a belt, Q, passing around it and around the smaller disk N. If 90 desired, the outwardly-projecting bracket may be dispensed with and the power applied di-

rectly to the smaller disk N, as will be readily understood.

R indicates the endless belt, which may be composed of leather, woven fabric, or any other suitable material which will form a cushion of sufficient yielding quality for the endless cutting-blade, the said belt encircling the rollers D and H, extending around their outer sides and passing in through the opening B' of the frame B and around the disk M, from which it receives its motion. A thin endless cutting-blade, S, of steel, having one of its edges sharpened, fits tightly around and travels with the exterior side of the endless belt R, except at the point where it spans the opening in the side of the frame, as shown. The endless belt R is composed of leather, woven fabric, or other suitable material, and the endless cutting-blade S presses tightly against the outside of the said endless belt, so that when the endless belt is caused to travel around the rollers of the circular frame B it will bear with sufficient pressure against the inner side of the thin flexible endless cutting-blade S to cause the same to travel with it by friction, as will be readily understood. The table has a slot, T, having rollers T' journaled at its edges, and the endless cutting-blade passes between these guide-rollers, bearing with its sides against the rollers; and U indicates a bracket or guide-arm having a slot in its horizontal portion, by means of which it is secured adjustably to the stationary frame B above the table, as shown, by means of a set-screw, U', while in the lower end of the downwardly-projecting arm of the bracket are journaled two guide-disks, V V, between which the endless cutting-blade passes above the material to be cut, which is lying on the table, the guide-rollers above and in the slotted table serving to guide and support the endless cutting-blade at the very point where it is operating on the fabric being cut, so that it will not break when in use. It will be seen that the cutting-blade will be carried along with the endless belt, and that cloth may be placed upon the table, and by bringing it to bear against the edge of the endless cutting-blade, the cloth will be cut by the said blade in the same manner as a board is cut by an endless saw-blade, and that a number of layers of cloth may be cut at the same time, thus enabling a number of patterns to be cut out of a piece of cloth at once, all the patterns cut out at the same time being exactly alike. It will also be seen that the endless belt R forms an elastic cushion for the endless cutting-blade, the cutting-blade encircling the said endless belt for its entire length, except at the point where it spans the aperture in the side of the frame B, and by this arrangement the endless cutting-blade is capable of being drawn to fit far more tightly and closely around the elastic cushion formed by the endless belt, which it incloses, than is possible where the cutting-blade comes in direct contact with the rollers of the frame, which are, of course, hard and inelastic. Where the driving-belt is brought into contact with the exterior of an endless cutting-blade, it tends, first, to exercise a "pull" or strain upon the endless blade before it reaches the point of contact, and after the cutting-blade leaves the point of contact with the drive-belt the belt serves to "push" the endless blade away from the said point of contact, as will be readily understood, thereby tending to "buckle" the cutting-blade as it leaves the point of contact with the drive-belt, no matter how tightly it may be sought to draw the said belt around the hard inelastic rollers upon which it is directly seated. By first placing the endless belt around the rollers of the frame, and then fitting the endless cutting-blade tightly and closely encircling the said belt, (the blade being drawn far more tightly around the elastic cushion formed by the belt than it is possible to draw it around the bare hard inelastic rollers,) all such danger of the endless blade being "buckled" is entirely prevented. Moreover, if the joint of the endless cutting-blade, or any inequality which might exist or be formed by accident in the sides of the said blade, should at any time catch or tend to retard, even for an instant, the progress of the blade through the thick pile of cloth or other material being cut, the elastic cushion beneath the entire blade, which the said blade incloses, would, through its elasticity, give sufficiently to prevent the breaking of the endless cutting-blade under strains which would tend to break a similar blade tightly encircling and in direct contact with hard inelastic rollers.

It is obvious that the lower series of rollers, around which the endless belt and cutting-blade pass, may be made adjustable in the same manner as the upper series of rollers without departing from the spirit of my invention. The outer flanged ends of the said rollers prevent the endless belt from working off of them, as will be readily understood.

Having thus described my invention, what I claim, and desire to secure by Letters Patent of the United States, is—

1. The combination, with a circular frame having an opening in one of its sides, of an endless belt supported by and traveling around the said frame, entering the opening in the side thereof and passing around a roller journaled within the said frame opposite the said opening, and an endless cutting-blade fitting tightly around and traveling with the exterior side of the endless belt, except at the point where it spans the opening in the said frame.
2. The combination, with a circular frame having an opening in one of its sides and provided with a series of rollers upon one of its sides, of an endless belt supported by and traveling around the said rollers entering the opening in the side of the frame and passing around a roller journaled within the frame opposite the said opening, and an endless cutting-blade fitting tightly around and traveling with the exterior side of the endless belt, except

at the point where it spans the opening in the said frame.

3. The combination, with a circular frame having an opening in one of its sides, of the 5 lower series of rollers having the flanged outer ends and arranged as described, the semicircular roller-frame carrying the upper series of rollers journaled therein and pivotally secured at one of its ends to the side of the circular frame, means for supporting and adjusting 10 the free end of the said roller-frame, the endless belt supported by and traveling around the said rollers entering the opening in the side of the circular frame and passing around 15 a roller journaled within the frame opposite the said opening, and an endless cutting-blade fitting tightly around and traveling with the exterior side of the said endless belt, except at the point where it spans the opening in the 20 said circular frame.

4. The combination, with the circular frame having an opening in one side, of a bracket 25 adjustably secured thereto by means of a set-screw, said bracket being slotted at each end and having a pair of guide-disks journaled within the slot at one end and engaging with the set-screw at the other.

5. The combination, with the circular frame having the block secured to its side, of the 30 semicircular roller-frame having the series of rollers journaled therein and pivotally secured at one end to the side of the circular frame in such a position that its free end is normally supported by the said stationary block, and having pivotally secured to its free 35 end the slotted plate, and a set-screw passing through the said slotted plate into the said stationary block on the circular frame, an endless belt, and an endless cutting-blade, sub-

stantially as described, for the purpose set 40 forth.

6. The combination of the circular frame having an opening in one of its sides and having an outwardly-projecting bracket diametrically opposite to the said opening, a pulley journaled upon the side of the circular frame and having a belt-disk upon its outer side, a drive-pulley journaled upon the side of the outwardly-projecting bracket, a belt passing over the said pulley and around the belt-disk, the endless belt supported by and traveling around the circular frame, entering the opening in the side thereof and passing around the pulley journaled upon the side of the frame, and an endless cutting-blade fitting 55 tightly around and traveling with the exterior side of the endless belt, except at the point where it spans the opening in the side of the circular frame.

7. The combination, with the circular frame 60 having an opening in one of its sides, of the semicircular roller-frame carrying the series of rollers journaled therein, around which the endless belt and endless cutting-blade pass, and pivotally secured at one end to the side of 65 the circular frame, means for supporting and adjusting the free end of the said roller-frame, and the adjustable bracket having the guide-disks journaled therein, all constructed and arranged as described, for the purpose set 70 forth.

In testimony that I claim the foregoing as my own I have hereunto affixed my signature in presence of two witnesses.

JOSEPH THOMAS.
